CUT-OFF MECHANISM FOR CIGARETTE-ROD-FORMING MACHINES

William F. Grupe, Lyndhurst, N. J., assignor to Ebeo Machine Corporation, New York, N. Y., a corporation of New York

Application July 1, 1929, Serial No. 375,202

3 Claims. (Cl. 131—37)

This invention relates to improved cut-off mechanism for cigarette-rod-forming machines.

A primary object of the invention is to attain higher speed of severing and thereby increase the output of the cigarette making machine as a whole.

In severing cigarette-rods or the like, it is necessary for the knife to move not only across the length of the cigarette-rod or the like, but also longitudinally with that rod, because the rod is being continuously fed forwards, and if the knife did not move longitudinally with it as it was passing across it, there would not be a clean cut. In severing mechanism as heretofore constructed, it has been found that, owing to the complicated nature of the mechanism employed for moving the knife, it is impossible to work the severing mechanism as fast as the cigarette-rod or the like could be made and fed forwards. Consequently, the rod-making mechanism has had to be slowed down to bring it into accord with the relatively limited capabilities of the severing mechanism.

According to the primary feature of the present invention, there is provided a cigarette-rod or like severing mechanism comprising a knife which is anchored to turn with a carrier rotatable in the direction to carry the knife edge across the cigarette-rod or the like, and is controlled by means which oscillate it relatively to the carrier, in the direction along the length of the cigarette-rod or the like. Thus, the said carrier is not reciprocated or oscillated, which means that the parts which partake of this movement are relatively light, and, consequently, offer but little inertia to reversals of motion. Hence, the aforesaid higher speed is obtainable.

The knife may be anchored to the carrier in various ways, but it is preferred to hinge it, and one convenient way is to have the point of anchorage of the knife to the carrier at one end of the knife, and the cutting edge of the knife at the opposite end. This construction facilitates balancing of the rotary masses.

The means for oscillating the knife preferably comprises a member located at, and reciprocable along, the axis of rotation of the carrier. This is particularly advantageous, not only because it reduces the number of rotary parts which require to be balanced, but also because if applied to a knife which is hinged at one end, and has its cutting edge at the other end, it enables the requisite movement of the cutting edge longitudinally of the cigarette-rod to be obtained with

only a fraction of that movement in the said reciprocating member.

Further features and objects of the invention will be more fully understood from the following detail description and the accompanying drawings, in which

Fig. 1 is a central vertical section of one embodiment of my invention;

Fig. 2 is a sectional elevation on line 2—2 of Fig. 1;

Fig. 3 is a detail side elevation, broken away in central vertical section, of the knife blade head and its rotating supporting plate;

Fig. 4 is a front elevation viewed from the left hand side of Fig. 3;

Fig. 5 is a plan view of a knife blade;

Fig. 6 is a sectional elevation on line 6—6 of Fig. 4;

Fig. 7 is a perspective view of a resilient clamp and adjustable locking member for the knife blade;

Fig. 8 is a sectional elevation on line 8—8 of Fig. 3;

Fig. 9 is a diagrammatic view showing a flat face grinding wheel for grinding the taper of the knife blade; and

Fig. 10 is a diagrammatic side elevation showing the general assembly of my cut-off mechanism on a rod-forming cigarette making machine.

As above indicated, the present invention is particularly directed to the cut-off mechanism applicable for rod forming types of cigarette making machines. Since the detail construction of the cigarette making machine proper, exclusive of the cut-off mechanism, may be of the regulation or any other approved constructions, these parts are not illustrated in detail in the drawings. In Fig. 10 I have shown in diagrammatic side elevation, the frame 1 of the cigarette machine proper, at 2 the regulation chute for receiving the carded tobacco from the feeder proper of the machine. The web of cigarette paper is indicated at 3, supplied from the bobbin 4, and passed through the printer 5, to the guide plate 6 for deposition thereat of the shredded tobacco filler. At 7 is indicated the endless tube belt for transmitting the cigarette paper and deposited tobacco through the folder 8; the paste wheel of the rod-forming mechanism is indicated at 9. The formed rod is indicated at 10.

My cut-off mechanism is located at one end of the upper face of the bed 11 of the cigarette machine, at the usual location of the regulation cut-off mechanism.

A portion of the cigarette rod 10 is indicated at 110

10a entering the bellmouth 12 of the ledger plate holder 13, the ledger plate tube being indicated at 14. The discharge tube for discharging the severed individual cigarettes is indicated at 15, 5 and is supported by the bracket 16 from the ledger plate holder 13. As appears more fully hereinafter, the ledger plate holder 13 and ledger plate tube 14 are reciprocated along the path of travel of the cigarette rod 10a, therewith simultaneously reciprocating the discharge tube 15.

As indicated above, the knife of my cut-off mechanism proper is reciprocated while rotated by suitable mechanism at certain phases of its rotation, and as appears more fully hereinafter, 15 the reciprocation of the knife is effected simultaneously with a like reciprocation of the ledger plate holder during the stage of severing of the cigarette rod by the knife edge of the cut-off mechanism.

20 As one form of my invention, I have illustrated in the drawings, the knife blade head or holder 17, hingedly supported at 18 on the pivot pintle 19 passing through the opposite ears 20 of the knife head supporting plate 21. The supporting plate 25 21 is continuously rotated by adjustable securingment to the outer end of the shaft 22, as by the beveled gear 23 meshing with the beveled gear 24, the latter being secured to the vertical shaft 25 which is driven in any suitable manner, as from 30 the main shaft or countershaft of the cigarette machine proper. The supporting plate 21 is shown adjustably positioned at the outer end of the shaft 22 by the provision of a set screw 26 passing through its hub 27, the flanged end 22a 35 of the shaft 22 serving as an outer limiting stop for the hub 27.

The reciprocation of the knife blade head 17 is had by any suitable means providing for controlled pivotal movement of the head 17 during 40 the stage of rotation of the shaft 22 and the supporting plate 21.

As one form of reciprocating means for the head 17, I have shown the internal cam member 28, fixed to the standard 29 for reciprocating the inner shaft 30, which is square, i. e., polygonal, 45 see Fig. 8, the outer shaft 22 being hollow of like polygonal contour to slidably receive and rotate the inner shaft 30. The outer shaft 22 is not reciprocated, but is rotated as above set forth, in its spaced bearings 31, 32, which are of combined 50 thrust and roller bearing type. The outer end 33 of the shaft 30 is connected by the pin 34 and slot 35 connection to the knife head 17; the pin 34 may be in the form of a hinge pin secured by a cotter pin 36. At a suitable location on the inner shaft 30 is pinned the cam arm 37 carrying the cam roller 38, disposed in the cam groove 39 of the cam member 28, serving also as a housing 55 for the stated cam parts and with its extension 28a for the inner end of the inner shaft 30, for confining the required lubricating medium, as well as to protect the same from dust and other foreign matter.

The inner shaft 30 is tensioned outwardly by 60 the expansive coiled spring 40, disposed between the oppositely disposed thrust bearings 41, 42, located in the housing extension 28a, thereby maintaining the cam roller 38 in continuous engagement with the effective face of the cam groove 39. The adjustment indicated at 43 serves to 65 compensate for wear of the moving parts.

Any suitable means may be provided for reciprocating the ledger plate holder 13 simultaneously and to commensurate extent relative to 70 the reciprocation of the blade head 17 during

the phase of severing of the cigarette rod 11. As one form of such reciprocating means, I illustrate the closed cam 44, adjustably mounted on the outer shaft 22, the reciprocation being had by the cam arm 45 carrying at its one end the cam roller 46 received within the closed cam 44, the opposite end of the cam arm 45 being secured to or forming a part of the reciprocating slide 47 mounted between the slide plates 48, 48, to which slide 47 the ledger plate carrier 13 is secured. The closed cam 44 is adjustably positioned with respect to the shaft 22 for the purpose of attaining precise synchronization and extent of reciprocation of the ledger plate holder 13 (and therewith of the ledger plate 14) and the reciprocation of the shaft 30 (in turn reciprocating the knife blade head 17 and knife blade 49) at the moment of severing the cigarette rod 10. The adjustment of the cam 44 controlling the ledger plate 14 also affords adjustment to a limited extent for varying cigarette lengths, in combination with suitable change of gearing ratio for the drive of the knife head and corresponding adjustment of the relative setting and selected proper cam area of the cams 39, 44.

100 The bearing 31 is shown mounted on the standard 50.

The bearings 31, 32, their standards 50, 29, the slide 45 and associated parts, the internal cam 44 and its associated parts are preferably substantially housed within a suitable casing to provide for a splash or other lubricating system and protect against dust and foreign substances, and to preclude leakage of lubrication.

105 Preferably, the rotating head of the cut-off mechanism is protected by a guard casing, having suitable openings for the emergence of the severing edge of the knife blade 49 during the stage of rod-severing, and during the stage of whetting upon a suitable grinding element.

110 The rotating supporting plate 21 is preferably provided with the spaced lugs 51, 51, on opposite sides of the blade head 17, supplementing the hinged or equivalent support of the blade head 17 against undue lateral strain, while permitting the same to freely oscillate between the lugs.

115 In practice, the mean position of the plane of the severing edge 52 of the knife 49 is substantially at right angles to the cigarette rod 11 at the moment of cutting, the indicated position of the knife edge being exaggerated in the view of these parts shown in Fig. 1, as will be appreciated by those skilled in the art, since a maximum of displacement of approximately one-quarter of an inch for the extreme positions of the plane of the severing edge of the knife blade 120 is ample for the proper severing function.

125 I provide for the ready replacement of a fresh knife blade as well, as for compensation of the wear of the severing edge. As one form of such improvement, the rotating head 17 is provided with oppositely disposed grooved edges 53, 53, for slidably receiving the knife blade 49, see Fig. 5, combined with suitable clamping and adjustable locking means, such as the clamping element 54 of resilient material, having the laterally extending lug portions 55 adapted to be received within the opposite slotted flanges 53, and further having the downwardly turned front wing portion 56 and lateral wing portions 57, 57, 130 resiliently engaging under pressure the face of the knife blade 49, and further provided with the locking lug 58 adapted to pass through the slot 59, see Figs. 4 and 5, of the knife blade 49, 135 to engage the series of locking indentations 60, 140

see Figs. 3 and 4, for holding the knife blade in set position against the tendency of displacement by the centrifugal force and the reaction forces incident to severing the cigarette rod.

5 Preferably, the cut-off mechanism is provided with suitable whetting or grinding means, i. e., sharpening means, operative automatically upon the rotation of the knife blade. Such sharpening element is referred to herein as a disc, irrespective of its sharpening and/or grinding and/or whetting function and the material and shape employed for the same. Such disc is preferably positioned relative to the path of the severing edge 52 of the knife blade 49 to effect the desired 10 action without requiring movement of the disc in the direction of its axis, but preferably permitting rotation of the disc about its axis, effected either idly upon rotative engagement of the severing edge therewith or by positive drive 15 if preferred.

As one form of mounting of such disc, see Fig. 9, disc 61 is universally mounted for all possible positions of the plane of its effective face and for vertical height and rotary adjustment about the 20 vertical and the horizontal, and as shown comprises the bearing 62 rotatively receiving a suitable stud at one end of which the disc 61 is mounted concentrically with the axis of such stud, such stud being adjustably axially set by 25 the screw-threaded stud 63 having the manipulating head 64, the screw-threading being received within suitable threading on the inner face of the bearing 62, the bearing 62 and its post 65 being pivotally mounted on the vertical, supporting 30 post 66. The extent of pivotal adjustment of the bearing 62 is controlled by the set screw 67, the threading of the shank of which meshes with the threaded, tapped opening 68 in the post 66. The post 66 is adjustable to vertical height 35 by means of a suitable gear having the indicated manipulating head 69, the gear meshing with the circular rack gear teeth 70, and the rotative adjustment of the post 66 about the vertical being had by the worm 71, rotatively mounted in the 40 supporting hollow post 72, the worm being adjusted by its indicated manipulating head 73. The post 72 is mounted on any suitable support, such as on the bed 11 of the cigarette machine proper, as also appears from Fig. 10.

50 The worm 71 meshes with vertically extending teeth on the post 66, the series of teeth extending annularly about the post 66, and of sufficient vertical extension to provide for the required vertical movement of the post 66 in the vertical adjustment of the same by the adjusting head 69, as aforesaid.

From the above, it will be apparent that the speed of the severing means provided by my invention is at all times, when properly initially set, in accurate synchronism with the rod-forming mechanism and other actuated parts of the cigarette making machine proper, and insures proper functioning of my cut-off mechanism at any desired increased speed at which the rod-

forming mechanism and associated parts of the cigarette making machine may be effectively operated. At all speeds of operation of my cut-off mechanism, the coacting parts, to wit, the rotating knife blade and the ledger plate are reciprocated at the stage of severing in the direction and at substantially at the same rate of forward travel of the cigarette rod, the knife head and its supporting plate, as well as the ledger plate being reciprocated in the opposite direction during a 85 non-severing stage.

It will be further apparent that but little inertia arises in the movement of the reciprocated parts, and of a magnitude which does not affect the proper co-relation of the actuated parts for the full range of speed at which the rod-forming mechanism and the associated parts of the cigarette machine proper can be effectively operated.

I claim.

1. A cut-off mechanism for a rod forming cigarette making machine, comprising a rotary knife blade support, fixed bearing means for said rotary knife blade support, a knife blade, hinged means for mounting said knife blade on said knife blade support, means for rotating said knife blade support in synchronism with the rod forming mechanism, cam means for displacing said knife blade relative to said knife blade support during the stage of severing, ledger plate means for receiving the cigarette rod formed by the rod forming mechanism, and means for displacing said ledger plate means in the direction of travel of the cigarette rod during the stage of severing. 100

2. A cut-off mechanism for a rod forming cigarette making machine, comprising a rotary knife blade support, fixed bearing means for said rotary knife blade support, a knife blade, hinged means for mounting said knife blade on said knife blade support, means for rotating said knife blade support in synchronism with the rod forming mechanism, means for displacing said knife blade relative to said knife blade support during the stage of severing, ledger plate means for receiving the cigarette rod formed by the rod forming mechanism, and cam means for displacing said ledger plate means in the direction of travel of the cigarette rod during the stage of severing. 105

3. A cut-off mechanism for a rod forming cigarette making machine, comprising a rotary knife blade support, fixed bearing means for said rotary knife blade support, a knife blade, hinged means for mounting said knife blade on said knife blade support, means for rotating said knife blade support in synchronism with the rod forming mechanism, fixed cam means for displacing said knife blade relative to said knife blade support during the stage of severing, ledger plate means for receiving the cigarette rod formed by the rod forming mechanism, and means for displacing said ledger plate means in the direction of travel of the cigarette rod during the stage of severing. 115
